UNITED STATES PATENT OFFICE.

ENOS F. SCHLICHTER, OF PHILADELPHIA, PENNSYLVANIA.

SILO.

1,367,329.

Specification of Letters Patent.

Patented Feb. 1, 1921.

Application filed April 14, 1920. Serial No. 373,745.

To all whom it may concern:

Be it known that I, ENOS F. SCHLICHTER, a citizen of the United States, residing at 3321 North Sixteenth street, city of Philadelphia, county of Philadelphia, State of Pennsylvania, have invented certain new and useful Improvements in Silos, of which the following is a specification.

My invention relates to silos and similar structures involving the use of staves or blocks made of cement or other composition. The molded blocks are arranged in courses, the blocks having outwardly curved surfaces at one side edge of each of the same and correspondingly curved vertical recesses at the other side ends of the same, the convexly curved ends of the blocks fitting within the corresponding recesses of the adjoining blocks to form interlocking joints. The blocks of one course are interlocking with the blocks of the courses above and below the same by means of integral curved projections on the upper edges of the blocks which fit within correspondingly curved recesses extending upwardly from the lower surfaces of the blocks immediately above the same.

The object of my invention is to improve the construction of devices of the character referred to, in various particulars. One of the features of my invention consists in providing forwardly and downwardly extending horizontal flanges or lips on the blocks. These lips add to the strength of the construction and are also so formed as to provide horizontal grooves beneath the same in which the hoops surrounding the silo are located. The hoops are thus protected against rust or deterioration. In the preferred form of my invention vertical flanges are also provided to extend forwardly from the ends of the blocks in which the vertical concave recesses are formed. These flanges stiffen and strengthen the structure and also provide horizontal bearings on which the hoops are supported. Other features of my invention will appear more fully hereinafter in the following specification and appended claims.

In order that my invention may be more clearly understood attention is hereby directed to the accompanying drawings forming part of this application and illustrating certain embodiments of my invention. In the drawings Figure 1 represents a partial side elevation of a silo constructed in ac-

cordance with my invention, Fig. 2 represents a top plan view of the portion of the construction illustrated in Fig. 1, considered as taken on the line 2—2 in Fig. 1, Fig. 3 is an enlarged vertical section taken through a pair of blocks on line 3—3 of Fig. 1, Fig. 4 is an enlarged perspective view of one of the blocks which may be used for forming the bottom course of the silo, Fig. 5 is a similar view of one of the blocks which may be used in the course immediately above that in which the block shown in Fig. 4 is used, Fig. 6 is a top plan view of a block such as that shown in Fig. 4 with a portion of a hoop mounted in relation thereto, Fig. 7 is a perspective view of a modified form of block having no vertical end flange, and Fig. 8 is a vertical section similar to that shown in Fig. 3, taken through a pair of aligned blocks of the character shown in Fig. 7.

Referring to the drawings the silo is formed of blocks or staves which are molded from cement or similar composition. As is shown in Figs. 1 to 6 inclusive of the drawings, the bottom course may be made up of blocks of the character of that shown at 1 in Fig. 4. The next course above the bottom course may be made up of blocks of the character of that shown at 1'.

All of the blocks in each horizontal course form interlocking joints with each other. Each block is provided at one end with a convexly curved surface 2 and each block is provided at its other end with a corresponding concavely curved recess 3.

Blocks of one course are also interlocked with the blocks of the courses immediately above and below the same. Each block is formed with an upwardly extending curved projection 4 which preferably is of substantial height in relation to the height of the main body of the block and which also preferably has a length, at its base, which comprises a substantial part of the length of the entire block. The upwardly curved projections or ribs 4 are adapted to fit within correspondingly curved recesses 5 which are formed upwardly from the bottom surfaces of all of the blocks except those which are used to form the bottom course of the construction. Obviously, all of the blocks including those in the lower course, may be identical if desired, but there will, of course, be no function for recess 5 in blocks which are used at the bottom of the structure.

All, or some, of the blocks are formed

2

with integral horizontal lips or flanges 6 extending downwardly and forwardly from the front surfaces of the blocks. Also in the form of my invention illustrated in Figs. 1 to 6 each of the blocks is formed with a vertical integral forwardly extending flange or projection 7 at the end of the block in which the concave vertical recess 5 is formed. Each forwardly extending horizontal flange 6 curves downwardly and outwardly from a plane above the top of the recess 5 formed in the block. Each flange 6 extends from the base of the convex rib or tongue 2 at one end of the block to the vertical flange 7 at the other end of the block, with which it merges. Each flange 6 is provided on its under face with a horizontal groove 8, in which a hoop is adapted to be received.

20 In constructing the silo, the blocks 1 of the bottom course are positioned in desired circular formation, with the convex end surfaces 2 on one block positioned within corresponding recess 3 at the adjacent end 25 of the next block. With this construction all of the vertical ribs 7 will extend forwardly, as is indicated, for example, in Fig. 2. To aid in securing the blocks of each course together, vertical channels 9 are 30 preferably formed at the outer ends of the concave surfaces 2 so that cement or the like may be placed in the channels thus formed when the blocks of a course are positioned in the desired circular arrangement.

35 The blocks of the bottom course being positioned, the blocks of the course next above the same are laid, the upwardly curved extensions 4 of the bottom blocks fitting within recesses 5 of the blocks immediately above 40 the same. The blocks of the various courses above the second will be laid in the same manner, the projection 4 of each block fitting within the recess 5 of the block immediately above the same, and various contacting surfaces of adjacent blocks being cemented together.

45 A continuous doorway may be provided, as is indicated at 10 in Fig. 1, the door frame preferably being provided by the vertically aligned end flanges 7 of the blocks each side of the doorway. Any desired form of removable door construction may be mounted within the doorway thus formed. The hoops 11 are extended around the silo at various 50 levels. These hoops, for example, may be positioned in alignment with the horizontal joints formed between each alternate pair of vertical courses as is indicated in Fig. 1. Assuming, for example, that a hoop is to be 55 positioned around the silo on a level with the upper surface 12 of each block of the bottom course, referring to Figs. 1 and 4, the hoop will be supported on the top surface of each forwardly extending vertical 60 flange 7, and will be received within the

horizontal groove 8 of the flange or lip 6 of the blocks of the next course above the same. When the blocks are positioned, the flanges or lips 6 will form a practically continuous aligned horizontal flange entirely 70 around the silo, except for the space provided by the doorway opening.

The hoops when so arranged will be entirely protected by the flanges 6 from the rain and weather. The flanges 6 will also 75 strengthen and stiffen the blocks at the points at which the same have been weakened by the formation of the recesses 5. The vertical flanges 7 provide masses of material in which the vertical recesses 3 may 80 be formed without weakening the structure; they also provide surfaces on which the hoops 11 are supported, and stiffen and strengthen the construction generally.

Each hoop, resting on the top surfaces 12' 85 of the vertical ribs 7 of a course of blocks, will bear against the outside edges of the convex surfaces 2 of the course of blocks immediately above the same. It is preferable, however, to distribute the pressure of 90 the hoops more evenly over the surface of the blocks. Accordingly I preferably provide the blocks 1, that is, the blocks of each course below a hoop, with integral forwardly extending horizontal flanges 13 95 which extend in approximate alignment with the base portion of the upward extensions 4 of the blocks. The outer or forward surfaces of these lugs or flanges 13 are given a curvature, as is indicated in Fig. 4, which 100 may be approximately the curvature assumed by the hoop in extending entirely around the circular or otherwise curved complete structure. With this arrangement, the hoops will bear against the forward 105 faces of the lugs 13, substantially throughout the lengths of the lugs, and will also press against the convex end surfaces 2 of the blocks of the course immediately above the same.

110 The doorway 10 should be provided with spreaders, to complete the same. These spreaders may be of any usual or desired character. I have illustrated tubes or pipe sections 14, which may be mounted in position between the vertical flanges 7 constituting the side frames of the doorway opening, the hoops 11 being illustrated as extending through the tubes 14. Obviously, different forms of spreaders may be used if 115 desired and it is not essential that the hoops should extend through the same, or across the doorway opening. The hoops may take the form of round iron members, or of cables or the like as desired.

120 I have illustrated in Figs. 7 and 8 a modified form of block which may be used, this construction being the same as that previously illustrated except that the vertical end flanges 7 are omitted. As is shown 125

block 1^a may be provided with a convexly curved end surface 2^a at one end and with the concavely curved vertical recess 3^a formed in the rear edge at the other end. 5 The block illustrated is also provided with an upwardly projecting portion 4^a at the top and with the recess 5^a extending upwardly from its lower surface. The forwardly and downwardly extending horizontal flange 6^a extends from the base of the convexly curved tongue or end portion 2^a, completely to the other end of the block, so that the horizontal flanges 6^a of all of the blocks in a horizontal course will abut 10 against each other end to end, so that all of the grooves 8^a formed in the bottom surfaces of the flanges, will form a practically continuous groove or channel in which a hoop may be mounted. With this construction 15 it is advisable that the blocks which are arranged immediately at each side of the doorway opening be provided with vertical flanges 7 on their ends which are adjacent to the opening, to form a doorway frame in 20 the same manner as has been previously described in connection with Fig. 1.

It is advisable that the channels 8 or 8^a should be outwardly curved in a horizontal plane to correspond to the curvature of the 30 front surfaces of lugs 13, so that the hoops, which extend around the circular structure can lie comfortably between the front surfaces of lugs 13 and the front walls of the grooves or channels 8 or 8^a.

35 It will be noted that with the construction described each hoop bears against the lugs 13 of the blocks of one course, that is to say, against the front surfaces of the upward projection 4 of said blocks, and also against 40 the lower portions of the convex ends of the blocks of the course immediately above the same. By this construction the pressure of the hoops against the blocks is more uniformly distributed than if the hoops bore 45 against the end portions only of the blocks, and at the same time the pressure of each hoop is exerted against the blocks of two superposed courses.

It should be understood that my invention 50 is not limited strictly to the details of construction described but is as broad as is indicated by the accompanying claims.

What I claim is:

1. In a silo, the combination of blocks 55 arranged in courses, said blocks having interlocking projections and recesses, all of the blocks of certain courses having alined horizontal flanges formed on their outer surfaces, extending outwardly from the body of the silo, and removable hoops extending about the silo, and in contact with the outer surface of the same, immediately below said flanges.

2. In a silo, the combination of molded 60 blocks arranged in courses, and having pro-

jections and corresponding recesses at their vertical and horizontal edges to form interlocking joints with each other, all of the blocks of certain courses having integral alined horizontal lips extending downwardly 70 and outwardly, to form channels between the same and the body of the silo, and removable hoops mounted in said channels and contacting against the outer surface of the silo.

3. In a silo, the combination of molded 75 blocks arranged in courses, having tongues and grooves at their side edges to form vertical joints, the blocks of one course having ribs extending upwardly from their top surfaces intermediate their lengths, and the 80 blocks of the next course above having their lower surfaces recessed to receive said ribs, the recesses extending entirely through said blocks from front to back, the blocks of said upper course having downwardly and outwardly extending integral portions in front 85 of the recesses, said integral portions having horizontal channels formed therein, and a removable hoop mounted in said channels.

4. In a silo, the combination of molded 90 blocks arranged in courses, and having projections and corresponding recesses at their vertical and horizontal edges to form interlocking joints with each other, all of the blocks of certain courses having integral 95 alined horizontal lips extending downwardly and outwardly, with horizontal channels extending upwardly from the lower surfaces thereof, and all of the blocks of the courses immediately below said courses having 100 forwardly extending projections adjacent their ends, and hoops mounted in said channels beneath said lips and resting on said last named projections.

5. In a silo, the combination of blocks arranged in courses, said blocks having interlocking projections and recesses formed at 105 their tops and bottoms, all of the blocks of certain courses having alined horizontal flanges formed on their outer surfaces, and 110 hoops extending about the silo immediately below said flanges, arranged to bear against the said projections of the blocks of the courses below the blocks having said flanges and against the end portion of the blocks 115 having said flanges.

6. In a silo, the combination of blocks arranged in courses, said blocks having interlocking projections and recesses formed at 120 their tops and bottoms, said projections and recesses being of lengths less than those of said blocks, said blocks having convexly curved vertical end portions, and hoops extending about the silo, each hoop being arranged to bear against the outer faces of said 125 projections of the blocks of one course and against the outer surfaces of said vertical end portions of the blocks of the next course, horizontally alined therewith.

7. In a silo, the combination of blocks ar- 130

5 ranged in courses, having interlocking projections and recesses, certain of said blocks having vertical forwardly directed flanges at one end of each and all of the blocks of
 10 5 certain courses having horizontal forwardly directed flanges adjacent their lower edges, and hoops extending about the silo, resting on some of said vertical flanges and protected from the rain by said horizontal flanges.

15 8. In a silo, the combination of blocks arranged in courses to form a complete silo with a vertical doorway opening therein, the blocks adjacent said opening having aligned vertical outwardly projecting flanges at one edge of each to form the doorway frame, the blocks of certain courses having integral aligned horizontal flanges on the outer surfaces thereof, and hoops extending
 20 20 about the silo immediately below said flanges and resting on some of said vertical flanges.

25 9. In a silo, the combination of blocks arranged in horizontal courses, each block having a vertical outwardly projecting enlargement at one end with a vertical recess of concave section formed in the inner surface and entirely through the block from front to back of said enlargement, and a convexly curved vertical surface at the
 30 30 other end, said convexly curved end portions fitting within said vertical recesses, said convexly curved end portions having

vertical channels formed therein, and cement in said channels.

10. In a silo, a molded block having a 35 body portion with a convexly curved vertical portion at one side edge, a forwardly projecting vertical flange at the other side edge, with a concavely curved vertical recess formed in the side edge at the rear thereof, 40 and a recess extending upwardly from the bottom surface of said body portion, and a horizontal flange extending outwardly and downwardly from the front surface of said body portion, to cover said upwardly extending recess, said flange joining said vertical flange at one end of the block.

11. In a silo, a molded block having a vertical tongue of curved section at one end, a vertical recess of corresponding section at 50 the other end, a curved extension projecting upwardly from the upper surface of the block intermediate its ends and a horizontal lug extending forwardly from the front surface of the block, in alignment with the base 55 of said upwardly projecting extension, the forward surface of said lug being convexly curved in a horizontal plane.

 HARVEY T. SCHLICHTER.

It is hereby certified that in Letters Patent No. 1,367,329, granted February 1, 1921, upon the application of Enos F. Schlichter, of Philadelphia, Pennsylvania, for an improvement in "Silos," an error appears in the printed specification requiring correction as follows: Page 4, lines 27-28, claim 9, strike out the words "and entirely through the block from front to back"; and that the said Letters Patent should be read with this correction therein that the same may conform to the record of the case in the Patent Office.

Signed and sealed this 15th day of March, A. D., 1921.
